JOHN G. GLOECKLER, OF BROOKLYN, NEW YORK.

COMB-CLEANER.

1,250,446.

Specification of Letters Patent. Patented Dec. 18, 1917.

Application filed September 12, 1916. Serial No. 119,779.

To all whom it may concern:

Be it known that I, JOHN G. GLOECKLER, a citizen of the United States of America, residing at New York city, borough of Brooklyn, in the county of Kings and State of New York, have invented certain new and useful Improvements in Comb-Cleaners, of which the following is a specification.

This invention has special reference to improvements in toilet devices and more particularly to an improved comb cleaner.

A particular object of the invention is to provide a device of simple and novel construction, as well as one which will serve as a practical and useful ornament to a dresser or the like, and by which various types of combs can be cleaned of dirt and grease from between the teeth thereof, thereby insuring that the comb will be kept in a sanitary condition at all times.

A further object of the invention is to provide an improved comb cleaner which includes a tray having suitable uprights thereon for supporting a series of tensioned wires disposed in crossed relation so as to vary the distances between the wires to accommodate and permit thorough cleaning of fine combs or combs of medium or coarse teeth formation, suitable means being provided for tensioning the wires or cleaning strands, while positioned at the ends of the device are brushes for removing the foreign matter scraped from the teeth of the comb by said wires and depositing the same on the tray whereby such foreign matter may be taken care of without being scattered about.

With the above objects and others in view, as will appear as the description proceeds, the invention comprises the various novel features of construction and arrangements of parts which will be more fully described hereinafter and set forth with particularity in the claims appended hereto.

Reference is had to the accompanying drawings forming a part of this application, in which like characters indicate the corresponding parts throughout the several views and wherein,

Figure 1 is a plan view of the improved comb cleaner.

Fig. 2 is a side elevation of the device taken partly in section on the line II—II of Fig. 1.

Fig. 3 is a fragmentary end elevation partly in section looking toward the right-

hand end as shown in Figs. 1 and 2, partly in section and with the brush removed, and

Fig. 4 is a fragmentary sectional view taken on the line IV—IV of Fig. 1.

As illustrated in the drawings, the improved comb cleaner includes a base 5 in the form of a tray or pan with a surrounding flange portion 6 which is turned up on a slight curve, while the tray is curved longitudinally on a radius of about one-fourth inch higher in the center than at the ends, as is clearly shown in Fig. 2. Suitable tread-pieces or cushion tips 7 may also be provided on the bottom of the tray to avoid scratching polished surfaces upon which the device may be supported, said tread-pieces being preferably of rubber or the like.

Extending upwardly from the tray near each end and formed with or fixed thereto in any preferred manner, are a pair of opposed and spaced parallel uprights 8 and 9 respectively. These uprights are preferably attached to the base or tray through the medium of reduced extensions 10 which are extended through and riveted to the bottom of the tray as shown at 11, thus providing a firm attachment between the uprights and the tray whereby the uprights are supported to withstand the necessary strain incident to the cleaning of combs, while the bending or curving of the base or tray upwardly at the center and providing a flange entirely around the same, not only strengthens the tray to resist strain incident to the cleaning operation, but also prevents the dirt and foreign matter from falling off of the tray.

Connecting the opposite pairs of uprights 8 are notched spacing and guide-rods 12 and directly beneath and spaced from the guide-rods 12 and also connecting the uprights are shafts 13. The rods 12 are fixed or anchored at their ends in the uprights near the upper ends of the latter and parallel to the base or tray, and are provided with a series of spaced notches 14 which may be formed by notching, recessing, grooving or threading the rods throughout their lengths so as to accommodate and hold in spaced relation a plurality of cleaning wires or strands 15. These strands are disposed in pairs crossed at the center and are preferably made up of a single section of wire or other material, spring wire of 26 gage being preferably employed and crossed centrally between the

rods as shown at 16, while the ends of the strands are guided over the rods and equidistantly spaced apart through the instrumentality of the grooves or recesses therein, 5 the single section of wire producing said strands being looped or rebent at each end as shown at 17 and said loops being engaged around a series of pegs or pins 18 projecting angularly in a downward direction from 10 the shafts 13 toward the ends of the tray and being preferably headed to prevent displacement of the loops as shown.

One of the shafts 13 is held stationary, that is, precluded from translating or rotating 15 through the instrumentality of a set-screw 19 engaged through one of the uprights and into a recess 20 of the shaft, or by other suitable means provided for this purpose.

20 The other shaft may in lieu of being stationary in the manner specified, to permit adjustment and holding thereof for maintaining the cleaning strands or wires under tension, be extended through one of the uprights as shown at 21 and a bracket-plate 22 is secured to the outer face of said upright as shown at 23 over the end portion 21 of said shaft 13 to turn freely through an aperture in the bracket-plate. A worm 30 gear 24 is fixed to the end 21 of said shaft and the bracket-plate is provided with a pair of apertured ears 25 carrying a worm shaft 26 which is held from translation in said ears as bearings, but which is adapted 35 to be turned through the medium of a key or finger-piece 27 mounted on the free end of the worm shaft. In this manner the shaft 13 to which the worm gear is operatively connected, may be turned for drawing 40 the wires taut and keeping the same under tension.

Positioned at the upper ends of the uprights are inwardly facing longitudinal, grooved guideways 28 produced by horizontally flanged pieces formed with or secured to the uprights and projecting outwardly therefrom toward the ends of the tray as is clearly illustrated. These guideways each accommodate the head portions 29 of 50 brushes having the bristle portions 30 thereof wired to the heads as shown at 31 and extending inwardly in opposite directions toward each other above the cleaning wires or strands so as to be contacted by the comb 55 when the latter is moved toward the ends of the cleaner for removing the foreign matter from the comb.

In the use of the device, the comb is engaged with the wires at the cross portions 60 thereof and moved toward either end so that the wires will scrape the side portions of the teeth and thereby loosen the dirt and grease which will be removed or carried off by the brush and deposited in the tray. 65 By engaging the comb and moving it to-

ward the opposite ends, both sides of the comb will be cleaned. For a medium size fine comb, the brushes can be moved longitudinally in their guideways or put forward toward the center as far as possible so as 70 to extend over the cleaning wires, where the spread or spacing of the wires is too great at the base ends thereof where engaged over the spacing and guide-rods. For a coarse comb the brushes are to be flush with the 75 back portions of the guides so that the bristles will hardly extend over the wires and where the comb is rounded, as for instance, a coarse rounded tooth lady's comb, the brushes are to remain flush at the back 80 and the comb should be zig-zagged across the cleaning wires at it is pulled along the same in either direction so that the wires will come in contact with the teeth on all sides in addition to moving the comb up and 85 down to efficiently clean it. The wires at the terminals or spacing rods are preferably made twelve to the inch and crossed at the center for ordinary combs and the device may be made in different styles varying the 90 spacing of the wires for fine combs to about twenty-four to the inch, and for ladies' or other coarse combs, about eight to the inch, the wires being crossed in the center in each instance or said wires may be spaced apart 95 eight to the inch at one end and twenty-four to the inch or otherwise at the opposite end so as to accommodate both coarse and fine combs. The base and other parts may be made of pressed steel or cast iron or otherwise, depending upon the cost of production and sale price, and is very efficient for use in barber shops, as the comb can be cleaned in a very short interval of time, and if necessary, sterilized or otherwise treated in 100 addition to insure an absolutely sanitary condition.

From the foregoing description, taken in connection with the accompanying drawings, the advantages of the construction and of the method of operation of the device will be readily apparent to those skilled in the art to which the invention appertains and while I describe the principle of operation of the invention, together with the 110 device which I now consider to be the best embodiment thereof, I desire to have it understood that the device shown is merely 115 illustrative, and that such changes may be made when desired as are within the scope 120 of the device as claimed.

Having thus described my invention, what I claim as new and desire to secure by Letters Patent of the United States is:

1. A comb cleaner comprising spaced 125 pairs of uprights, rods connecting the uprights and having notches therein, shafts journaled between the uprights, a series of cleaning strands extending between the rods and connected to the shafts for being held 130

under tension by rotation of the shafts, and means for anchoring the shafts when adjusted to tension the strands.

2. A comb cleaner comprising spaced 5 pairs of uprights, rods connecting the uprights and having notches therein, shafts supported beneath the rods, a series of cleaning strands extending between the rods and connected to the shafts for being held 10 under tension, guideways carried by the uprights at the ends of the strands, brushes adjustable in said guideways over the latter and means for holding the shafts against movement with the strands under tension.

15 3. A comb cleaner comprising spaced supporting members having uniformly recessed tension members, a strand of wire or the like stretched between said tension members in zig-zag relation with the ends there- 20 of looped, headed pegs carried by the tension members for engagement by said looped ends, and brushes longitudinally adjustable above the ends of the cleaning members pro- 25 vided by the strand as and for the purpose described.

4. A comb cleaner comprising a flanged tray-forming base curved upwardly at the center and toward its ends, spaced parallel uprights at the ends of the tray, a rod ex- 30 tending across each pair of uprights and having a series of equidistantly spaced circular grooves therein, said rods being in parallel relation, shafts rotatably supported in the uprights beneath the rods, pegs car- 35 ried by the shafts, a strand of wire or the like looped around the pegs and extending over and between the rods to provide a series of longitudinal cleaning members ar- 40 ranged in series with the respective pairs disposed in opposite divergent relation, hori- 45 zontal guides at the upper ends of the up- rights and facing inwardly in opposed rela-

the brushes extending over the same to vary the degree of movement of a comb on said cleaning members with the teeth extending between said members whereby the wires will scrape foreign matter from said teeth, 50 and means for turning one of the shafts to hold the strand producing the longitudinal cleaning members, under tension.

5. A comb cleaner comprising a flanged tray-forming base curved upwardly at the center and toward its ends, spaced parallel uprights at the ends of the tray, a rod ex- 55 tending across each pair of uprights and having a series of equidistantly spaced circular grooves therein, said rods being in parallel relation, shafts rotatably supported in the uprights beneath the rods, pegs car- 60 ried by the shafts, a strand of wire or the like looped around the pegs and extending over and between the rods to provide a 65 series of longitudinal cleaning members ar- ranged in series with the respective pairs disposed in crossed divergent relation, hori- 70 zontal guides at the upper ends of the up- rights and facing inwardly in opposed rela- 75 tion, brushes having heads slideable horizon- tally in said guides and longitudinally of the cleaning members with the bristles of the brushes extending over the same to vary the degree of movement of a comb on said cleaning members with the teeth extending between said members whereby the wires will scrape foreign matter from said teeth, 80 a set-screw for holding one of said shafts against turning and a key operated worm gear connected to the other shaft for turning the latter and holding the cleaning members of the strand under tension.

In testimony whereof I affix my signature in presence of two witnesses.

JOHN G. GLOECKLER.
